UNITED STATES PATENT OFFICE.

EUGENE L. HOWE, OF CLEVELAND, OHIO, ASSIGNOR TO THE EBERHARD MANUFACTURING COMPANY, OF SAME PLACE.

CLIP-COCKEYE.

SPECIFICATION forming part of Letters Patent No. 434,045, dated August 12, 1890.

Application filed March 18, 1889. Renewed February 21, 1890. Serial No. 341,288. (No model.)

To all whom it may concern:

Be it known that I, EUGENE L. HOWE, of Cleveland, in the county of Cuyahoga and State of Ohio, have invented certain new and 5 useful Improvements in Clip-Cockeyes; and I do hereby declare the following to be a full, clear, and exact description of the invention, such as will enable others skilled in the art to which it pertains to make and use the same.

My invention relates to improvements in clip-cockeyes for harness, the same having a universal joint; and it consists in certain features of construction, and in combination of parts hereinafter described, and pointed out 15 in the claim.

In the accompanying drawings, Figure 1 is a side elevation, and Fig. 2 a plan.

A represents the clip, the same having straps *a*, that embrace and are riveted to the tug, 20 and having a circular loop *a'*, the wire of which is round in cross-section. This variety of clip is cheaply made of wrought metal by passing the same through rolls having grooves of such variable form and depth as will shape the 25 clip ready for bending.

The cockeye *B* consists of a link approxi- mately in the form shown, having an eye *b* for engaging loosely with the loop of the clip, and having a larger eye *B'* for engaging, for

instance, the fastening on the whiffletree. 30 The side members of the cockeye curve inward, as shown, so that the loop of the clip is confined in eye *b*; but the sides of the cockeye are separated far enough to receive a strap *a* of the clip in assembling the parts, 35 and to brace and strengthen the sides of the cockeye at the bend thereof, where they are reinforced by slight external ribs *b'*. With my improved construction the desired strength is had with less metal than with the ordinary 40 forms of clip-cockeye, and consequently can be made at less initial cost.

What I claim is—

A clip-cockeye consisting of a clip having side bars adapted to embrace a tug and a 45 curved cross-bar, and a cockeye consisting of a link having its side walls deflected inwardly to form two eyes which communicate, and reinforcing ribs located at such deflections of the walls, substantially as set forth. 50

In testimony whereof I sign this specification, in the presence of two witnesses, this 9th day of November, 1888.

EUGENE L. HOWE.
